UNITED STATES PATENT OFFICE.

CLARENCE F. WHIPPLE AND EFFINGER E. WHIPPLE, OF RACINE, WISCONSIN; SAID EFFINGER E. WHIPPLE ASSIGNOR TO SAID CLARENCE F. WHIPPLE.

END-BOARD FASTENING.

SPECIFICATION forming part of Letters Patent No. 225,544, dated March 16, 1880.

Application filed January 13, 1880.

To all whom it may concern:

Be it known that we, CLARENCE F. WHIPPLE and EFFINGER E. WHIPPLE, both of Racine, in the State of Wisconsin, have invented 5 certain new and useful Improvements in End-Board Fastenings for Wagon-Boxes, of which the following is a specification, reference being made to the accompanying drawings, which form a part thereof.

10 Our invention relates to a mode of operating the tie-rod with reference to the side-boards, whereby the end-board may be removed or let down without withdrawing the tie-rod therefrom.

15 It consists, primarily, in slotting the side-boards to admit the tie-rod by a lateral instead of the customary longitudinal movement of the latter; and, secondarily, in applying metal plates to the slots, which plates are provided with lugs or recesses adapted to hold 20 the head and nut of the rod firmly to the side-boards.

Figure 1 shows the slot in the side-board horizontal, with tie-rod therein, and plate fitted to receive the nut on the latter. Fig. 2 shows the opposite plate fitted to receive the head of the rod. Fig. 3 shows the head-plate recessed, and is a section of side-board and plate through the horizontal slot. Fig. 4 25 shows the slot vertical.

A is the end-board, and B the side-board, of a wagon-box. C is the tie-rod, having a solid head, T, at one end and a screw and nut, N, at the other. D D are slots in the 30 side-boards. G G' are cleats secured to the side-boards, and H H similar cleats fastened to the end-board. E E are metal plates, slotted to coincide with the slots in the side-boards, and firmly secured to the latter. They 35 are provided with lugs F F, behind which the head and nut or other fastening of the tie-rod are drawn and held in securing the end-board in place.

The head of the rod is preferably T-shaped, 40 as shown, and the lugs or recess by which it is held straight, while the lugs or recess on the opposite plate will be curved or otherwise

shaped to conform with the nut or other fastening used.

The tie-rod is held in place upon the end-board by the cleats H H, behind which it passes, and, being admitted laterally into the slots, does not need to be withdrawn from the end-board when the latter is removed or inserted. The nut N need not, therefore, be run 55 entirely off the rod, but only so far as to allow the nut and head to pass the lugs F F.

For the same reason a permanently-pivoted cam or other permanent device may be attached to the rod in place of the nut, with the 60 advantage, in both cases, of great convenience and no liability to loss.

In connection with the horizontal slot, additional fastenings—as hinges or dowel-pins L L—may be used, though by locating the rod 65 C near the middle of the end-board special stays for the bottom need not be used, the rod co-operating with the cleats G G, against which the end-board rests, to hold the same firmly upright and in place.

70 Instead of the continuous rod C, short end rods may be secured to the end-board, and a tightening device applied to each.

The plates E are not in all cases necessary; but they are in many cases indispensable and 75 always desirable. They are, moreover, preferably of form to enter and cover the inner surface of the slot, as shown in Figs. 1, 2, and 3.

In the absence of plates the side-boards will 80 be themselves recessed.

When the slot is vertical, as shown in Fig. 4, the usual external cleat, G', is used to receive the outward pressure, if any, upon the end-board.

85 Having thus described our invention, what we claim, and desire to secure by Letters Patent, is—

1. In an end-board fastening, the slots D D, in combination with the projecting rod C, or 90 its equivalent, and suitable devices for securing the rod within the slots, substantially as and for the purposes set forth.

2. The slotted plates E, provided with lugs

or recesses, substantially as and for the purposes specified.

3. The combination of slotted side-boards B, end-board A, hinges or dowel-pins L, and the tie-rod C, provided with suitable devices for securing its projecting ends in the slots, substantially as and for the purposes set forth.

4. The combination of slotted side-boards B, cleats G G', one or both, end-board A, and tie-rod, with suitable devices for securing the rod in the slots, substantially as described, and for the purposes specified.

In witness that we claim the above-described improvements as our invention we hereunto set our hands this 10th day of January, A. D. 1878.

CLARENCE F. WHIPPLE.
EFFINGER E. WHIPPLE.

In presence of—
JOHN C. HUGGINS,
D. J. MOREY.
